ATTORNEY.

UNITED STATES PATENT OFFICE.

GEORGE H. RICHARDS, OF PHILADELPHIA, PENNSYLVANIA, ASSIGNOR, BY
MESNE ASSIGNMENTS, TO AMOS J. LAMBORN, OF SAME PLACE.

PHOTOGRAPHIC VIGNETTING ATTACHMENT.

SPECIFICATION forming part of Letters Patent No. 459,938, dated September 22, 1891.

Application filed November 2, 1889. Serial No. 329,080. (No model.)

To all whom it may concern:

Be it known that I, GEORGE H. RICHARDS, a citizen of the United States, residing in the city and county of Philadelphia, State of Pennsylvania, have invented a new and useful Improvement in Vignetting Attachment for Photographic-Printing Frames, which improvement is fully set forth in the following specification and accompanying drawings.

10 My invention consists in forming a vignetting attachment of papier-maché, paper-pulp, or other plastic material, molded or pressed into shape, making a light, cheap, and durable article.

15 It also consists in setting out the face of the attachment, so that increased strength is obtained, and the light may be diffused to a greater extent and the vignette thereby made softer.

20 Figures 1 and 3 represent perspective views of vignetting attachments embodying my invention. Fig. 2 represents a longitudinal section on line $x-x$, Fig. 1. Fig. 4 represents a longitudinal section on line $y-y$, Fig. 3.

25 Similar letters of reference indicate corresponding parts in the several figures.

Referring to the drawings, A designates a vignetting attachment for a photographic-printing frame, the same being formed of 30 papier-maché or other plastic material, which is molded or pressed into shape between suitable dies, the main portion of the attachment being set out, thus increasing the distance between the line of the negative and the tissue-paper on the block, whereby the light is

diffused to a great extent and the vignette made softer, the shape of the attachment rendering it stronger and more durable. In Figs. 1 and 2 the set-out or raised portion of the face is inclined, being especially designed for 4c dark draperies, the higher portion having a greater spread of diffused light than the lower part.

As the attachment is formed by pressing, stamping, or molding, it is cheaper and lighter 45 than heretofore and possesses increased strength.

Having thus described my invention, what I claim as new, and desire to secure by Letters Patent, is—

1. A vignetting attachment for photographic-printing frames formed of plastic material having its face set out, said face portion being integral with the attachment, substantially as described.

2. A vignetting attachment for a photographic-printing frame formed of plastic material pressed or molded into shape and having its face set out, said face portion being integral with the attachment, substantially as described.

3. A vignetting attachment for photographic-printing frames consisting of a piece of plastic material pressed into shape and having an integral inclined face, substantially as and for the purpose set forth.

GEO. H. RICHARDS.
